UNITED STATES PATENT OFFICE.

JOHN B. GLOWACKI, OF CHICAGO, ILLINOIS.

DESIGN FOR A CANE OR UMBRELLA HANDLE OR SIMILAR ARTICLE.

48,512.

Specification for Design.

Patented Feb. 1, 1916.

Application filed October 3, 1914. Serial No. 864,950. Term of patent 3½ years.

To all whom it may concern:

Be it known that I, JOHN B. GLOWACKI, a citizen of the United States, and residing in the city of Chicago, county of Cook, and State of Illinois, have invented a new, original, and ornamental Design for a Cane or Umbrella Handle or Similar Article, of which the following is the specification, reference being had to the accompanying drawings, forming a part thereof.

In the drawings: Figure 1 is a side elevation illustrating the design of my cane or umbrella handle. Fig. 2 is a front elevation thereof. Fig. 3 is a top plan view thereof.

I claim:

The ornamental design for a cane or umbrella handle or similar article, as shown.

JOHN B. GLOWACKI.

Witnesses:

CHARLES W. HILLS, Jr.,

FRANK K. HUDSON.
